(57) **CLAIM**

The ornamental design for shrouds of a coffee machine, as shown and described.

DESCRIPTION

FIG. 1 is a front view of shrouds of a coffee machine, showing our new design;

FIG. 2 is a left side view thereof;

FIG. 3 is a right side view thereof;

FIG. 4 is a rear view thereof;

FIG. 5 is a top view thereof;

FIG. 6 is a bottom view thereof;

FIG. 7 is a front perspective view thereof; and,

FIG. 8 is a rear perspective view thereof.

The shade lines show surface contour.

The broken lines in the drawings depict environment of a coffee machine that form no part of the claimed design.

1 Claim, 8 Drawing Sheets
